UNITED STATES PATENT OFFICE.

HARRY A. SIMSROTT, OF CHICAGO, ILLINOIS.

PICTURE HANGER.

Application filed December 12, 1927. Serial No. 239,425.

This invention relates to improvements in picture hangers and more particularly to hangers for relatively large and heavy pictures which are hung on the walls of passageways and lobbies of theaters, hotels, and other public places.

These pictures, especially in theaters, are usually hung at the height of the average individuals so as to be best displayed, and are thus in positions to be touched by the servers and also to be hit or struck by individuals and crowds passing them with the result that with hangers as heretofore employed the pictures are moved or shifted out of proper alignment and are often injured or damaged by being completely knocked from the walls, especially when the passageways in which the pictures are hung are overcrowded. Moreover, the help or employees of the theater, when cleaning the pictures or the wall portions behind them or both, move or shift the pictures out of line and sometimes knock them from place.

The main object of my invention is to provide hanger means by when the pictures are maintained in proper positions on the walls and will be automatically returned to such positions on being moved or shifted out of the same either by individuals or crowds hitting or striking them in passing or by the help when cleaning the pictures or the wall portions behind them or both.

Another object of my invention is to provide hanger means which will permanently secure the pictures to the walls and thus prevent knocking the pictures from the walls as heretofore.

A further object of my invention is to provide hanger means which is simple in construction and inexpensive to make and which may be readily and easily applied to the pictures and walls, respectively, by screws or bolts or other ordinary fastenings.

The invention consists further in the matter hereinafter described and claimed.

In the accompanying drawings—

Fig. 1 is a front view of a picture hung on the wall by the hanger means of my invention;

Fig. 2 is a side view of the parts shown in Fig. 1 on an enlarged scale;

Fig. 3 is an enlarged horizontal sectional view taken on line 3—3 of Fig. 2; and

Fig. 4 is an enlarged longitudinal sectional view through one of the brackets and associated parts to show details of structure.

In the drawings, 1 indicates a framed picture and 2 the wall upon which the picture is hung.

The hanger means of my invention comprises a pair of bracket fixtures 3, 3 and a pair of suspension elements 4, 4. The bracket fixtures 3, 3 are secured to the wall 2 and to the rear side of the picture frame adjacent its lower edge in horizontal spaced relation and serve to hold the picture on the wall at a horizontal level at all times. The suspension elements 4, 4 are secured to the rear side of the picture and to the wall 2 above the horizontal center of the picture and allow the picture to hang at an outward inclination from the wall 2 as required for the best display of the picture. The bracket fixtures 3, 3 have resilient means which normally hold the picture on the wall in proper horizontal alignment and automatically return the picture to such alignment should the picture be moved or shifted laterally from either side.

Each bracket 3 is preferably made from a metal strip having a flat body portion 5 and outturned ends 6, 6. The body portion 5 is secured to the wall 2 by suitable fastening members 7, 7 which may be screws or bolts. The projections 6, 6 are apertured to receive a tube or rod 8 which extends between them and which rod is supported by the projections outward from the body portion 5 in parallel relation thereto. The ends of the rod 9 extend slightly beyond the projections 6, 6 and are there provided with fasteners, 9, 9 which may be in the form of cotter-pins 9, 9 inserted through apertures in the rod to hold the latter from endwise movement in the projections.

Associated with the brackets 3 are screw-eye fasteners 10, 10, the threaded ends of which are screwed into the frame of the picture at the respective brackets, there being a screw-eye for each bracket. The rods 8 of the brackets pass through the eyes of the fasteners 10 and thus provide a pivotal as well as a slidably support therefor.

The resilient means for each bracket 3 for normally holding the picture in proper horizontal alignment on the wall and for automatically returning the picture to such alignment when shifted or moved laterally out of the same, may take the form of a pair of coiled expansion springs 11, 11 which surround the rod 8 on opposite sides of the eye 10 and bear at their outer ends against the projections 6, 6 and at their inner ends either

against the eye or against washers 12, 12, which are on opposite sides of the eye 10. The springs 11 normally hold the eye 10 from sliding on the rods, but give when the 5 eyes in the lateral shifting of the picture are slid on the rods. The washers 12 may be cup-shaped so as to receive the inner ends of the springs 11, 11 and thus prevent the same from hooking on the eyes or engaging about 10 the same to bind the springs or prevent free turning movement of the eyes about the rod as the picture is swung toward and from the wall.

Each suspension element 4 is composed of 15 a stiff wire section 13, and a compression coiled spring section 14. The latter has one end hooked in an eye 15 which is secured to the frame of the picture 1, and the other end of the spring is hooked in an eye or loop 20 at the adjacent end of the wire section 13. The other end of the latter is hooked in an eye 16 which is secured to the wall 2. The spring sections 14 expand when the picture is pulled outward from the wall 2 beyond 25 its normal inclined display position and return the picture back to that position when the picture is released from such outward pull.

With the brackets 3 and suspension elements 4 fixedly secured to the wall 2 and to the frame of the picture, respectively, the picture is permanently attached to the wall and can not drop or be knocked from the same, thereby insuring the safety of the picture. With the brackets 3 fixed to the wall in horizontal alignment, the picture is always held or maintained at a horizontal level on the wall as no opportunity is afforded for the picture to swing out of that 40 position as when suspension cords or cables are used to hang the picture as heretofore. With the eyes 10, 10 on the rods 8, the picture may slide slightly when moved or shifted to the right or left against the tension of the springs 11, and the latter will automatically return the picture to its normal horizontal position as soon as the shifting force on the picture is released. Thus the hanger means of my invention will normally maintain the pictures in their proper horizontal positions on the wall even though hit or struck by individuals passing them or when moved or shifted when cleaning them or the wall portions behind them or both.

The details of structure and arrangement or parts shown and described may be variously changed and modified without departing from the spirit or scope of my invention. Moreover, the hanger means of my invention is applicable to all pictures and is not limited to those which are hung in public places. Furthermore, the hanger means of my invention may be also employed for hanging mirrors, plaques, and other devices of 65 the picture variety on walls, and in using

the term "picture" in the specification and claims, I use it in a broad sense to include these and similar devices.

I claim as my invention:

1. A picture hanger assembly, comprising means to be secured in horizontal position on a wall, means to be secured to the lower portion of the picture and having pivotal and horizontal sliding connection with said first mentioned means, resilient means 70 for automatically returning the picture to its normal position when slid laterally out of the same, and means for limiting the outward swing of the picture about its pivotal connection with said first means. 80

2. A picture hanger assembly, comprising brackets to be secured in horizontal spaced relation on a wall, rods carried by said brackets and disposed in substantially horizontal alignment, members pivotally and 85 slidably mounted on said rods and adapted to be secured to the lower portion of the picture for connecting the same to said rods, resilient means associated with said brackets and disposed to automatically return the picture to its normal position on said rods when slid laterally on the same, and means for 90 limiting the outward swing of the picture on said rods.

3. A picture hanger assembly, comprising 95 brackets with outwardly projecting parts and to be secured in horizontal spaced relation on a wall, rods carried by said parts and disposed in substantially horizontal alignment, eye members pivotally and slidably 100 mounted on said rods and adapted to be secured to the lower portion of the picture for connecting the same to said rods, coiled springs on said rods on opposite sides of the eye members for returning the picture to its normal position on said rods when shifted or moved along the same, and means for 105 limiting the outward swing of the picture on said rods.

4. A picture hanger assembly, comprising 110 means to be secured to a wall in horizontal position, means to be connected with the lower portion of the picture and having pivotal and horizontal sliding connection with said first mentioned means, resilient means 115 for automatically returning the picture to normal position when moved or shifted out of the same, and resilient elements to connect the upper portion of the picture with the wall. 120

5. A picture hanger assembly, comprising 125 brackets with outwardly projecting parts and to be secured in horizontal spaced relation on a wall, rods carried by said parts and disposed in substantially horizontal relation, eye members pivotally and slidably mounted on said rods and adapted to connect the lower portion of a picture thereto, coiled springs on said rods between said parts and located on opposite sides of said eye members, 130

washers on said rods on opposite sides of the eye members and being cup-shape to receive the inner ends of said springs, and connectors with coiled springs to connect the upper 5 portion of the picture with the wall.

6. A centering device of the character described, comprising a bracket having outwardly projecting parts, a rod extending between and supported by said parts, a member 10 slidably mounted on said rod between said parts, and resilient means co-operating with said member for normally holding the latter in normal position on the rod.

7. The combination with a picture and a wall, of a hanger for mounting the picture 15 on the wall, said hanger having means to be secured in horizontal position on one of the parts, means to be secured to the other part and having horizontal sliding connection with said first mentioned means, and 20 means for automatically returning the picture to its normal position when slid laterally out of the same.

In testimony whereof I affix my signature.

HARRY A. SIMSROTT.
